COMMUTATOR FOR ELECTRIC MOTORS

James E. Morrow, Butler, Pa., assignor of forty
per cent to John F. Thomas, Butler, Pa.

Application January 27, 1941, Serial No. 376,200

2 Claims. (Cl. 171—321)

This invention relates to commutators for electric motors and has for an object to provide a commutator which has increased life due to elimination of grounding of the commutator bars through the V ring which clamps the copper bars and the insulating mica strips in position.

Ninety per cent of short circuits causing commutator failure occur at the outer ends of the commutator bars and the present invention contemplates increasing the thickness of the insulation at this point by grooving the sides of the outer ends of the copper segment bars and cutting away the inner walls of the grooves at an angle of about 45°, and also cutting away the mica insulating segment in a similar manner, thus providing a radial space between the outer ends of the adjacent copper segment bars terminating at the bottom in a triangular space, such space being filled with insulating cement and providing effective insulation to prevent short circuiting.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation, partly in section, of a commutator constructed in accordance with the invention.

Figure 2 is an end elevation of the commutator looking toward the outer end or left side of Figure 1, and showing insulating cement between some of the copper segment rings and showing some of the rings in end elevation without the cement in the grooves thereof.

Figure 3 is a fragmentary plan view of the commutator looking in the direction of the arrows 3—3 of Figure 2.

Figure 4 is a diagrammatic view showing copper segments provided with grooves at the outer ends, widened by being cut back at an angle of 45° at the bottom of the inner walls, and showing in dot and dash lines how the mica segment between the rings is undercut below

the wear surfaces of the rings and cut away at its outer end.

Referring now to the drawing in which like characters of reference designate similar parts in the various views, 10 designates copper conducting segments arranged in the form of a cylinder and separated by mica segments 11 disposed between adjacent copper segments and extending only part way from the bottom of the copper segments to the tops or the wear surfaces of the copper segments as indicated diagrammatically by dotted lines in Figure 4, which dotted lines represent the planes of the outer end faces 12 of the copper segments and the cylindrical surface in which the wear surfaces 13 of the copper segments extend. The copper segments and the mica segments are undercut in the usual manner to provide dovetail base portions 14, a flange 15 of V-shape cross section, carried by the cylindrical body 16 of the commutator engaging the inner side, that is the side toward the electric motor, of the dovetail projection, while the conventional V ring 17 engages the other side of the dovetail projection of all of the copper segment bars and mica segment bars, the V ring being held in place by a clamp ring 18 which is threaded on to the end of the cylindrical body 16 of the commutator. So far the construction may be said to be conventional.

The invention, or improvement in commutator constructions, consists in forming grooves 19 on each end face 12 of the copper segment bars 11, the grooves opening through the side faces of the bars. The inner wall of each groove is cut back obliquely at an angle of about 45° to provide an inclined lower portion 20 of the bottom wall of the groove. The mica segment 11 is cut away obliquely at the lower end of the front edge to provide an inclined wall 21 which extends flush with the inclined portion 20 of the bottom wall of the groove 19 of the adjacent copper segment when the copper segments and mica segments are assembled.

The grooves 19, as well as the triangular spaces at the lower ends of the grooves formed by the inclined walls 20 of the copper segments and 21 of the mica segments are filled with insulating cement or other suitable insulating material of any type. By thus insulating the front ends of the copper segments from each other by insulation of greater thickness than a single mica sheet, and even increasing this insulation at the bottom portions of the front ends of the copper segments by the triangular spaces formed at the

bottoms of the grooves, short circuiting between the V ring 17 and copper segment bars is eliminated and longer service greatly promoted.

In completing the construction of the commutator above described, insulating cement 22 of any suitable type is disposed between the copper segments and on top of the mica segments for a short distance at the front ends thereof. A band of cords 23 is disposed upon insulating material 24 interpolated between the V ring and the copper and mica segments, and an insulating layer of paint 25 is disposed upon the band. A ring of cement 26 is disposed between the inner end of the band and the lower ends of the outer faces 12 of the copper segment bars at the triangular spaces at the lower ends of the grooves of the bars, which spaces and which grooves are, as previously stated, filled with cement 29 and 30, or any desired insulating material.

From the above description it is thought that the construction and operation of the invention will be fully understood without further explanation.

What is claimed is:

1. A cylindrical commutator comprising conducting segments having outer peripheral brush engaging faces and radially disposed outer end faces, sheets of insulating material between the

segments, said segments and said sheets having dovetail extensions, means engaging said dovetail extensions and holding the segments and sheets assembled, the outer end faces of the segments being provided with radially disposed grooves opening through the side faces of the segments, said grooves having portions of the inner walls inclined at about an angle of 45° to said outer end faces to provide triangular spaces opening through the inner peripheral faces of the segments, and insulating material in said grooves and in said triangular spaces coating with the insulating sheets in preventing short circuiting between the outer ends of the segments and said securing means.

2. A commutator comprising separated conducting segments having a brush bearing surface, an insulating sheet between each adjacent pair of segments extending from below the brush bearing surface to the surface opposite the brush

bearing surface and filling the space between the segments, said segments and insulation being cut away obliquely at the outer ends adjacent to said opposite surface to form substantially triangular spaces, and additional insulation between the segments in said spaces extending through said opposite surface.

JAMES E. MORROW.
